UNITED STATES PATENT OFFICE

BENJAMIN W. JONES, OF SCHENECTADY, NEW YORK, ASSIGNOR TO GENERAL ELECTRIC COMPANY, A CORPORATION OF NEW YORK

MOTOR CONTROL

Application filed January 9, 1922. Serial No. 527,840.

My invention relates to the control of electric motors, and it provides improved means whereby electric motors may be started and stopped and generally controlled in a safe, reliable and efficient manner.

More specifically, the present invention relates to an improvement of the system of motor control for which Eugene R. Carichoff and I filed an application for patent, Serial 10 No. 354,030, on January 26, 1920. In the said application, Eugene R. Carichoff and I have disclosed and claimed an improved form of control in which the acceleration of the motor is governed by the voltage drop across the 15 starting resistor or resistors and a time factor. The arrangement among other things involved the use of an electromagnetic switch or electromagnetic relay which is biased to one position and has two windings, one for 20 governing the opening of the relay and the other for governing the closing thereof. The closing winding is connected across the resistor controlled by the relay so that the relay will not be closed to effect the short circuiting 25 of the resistor until the voltage drop across the resistor has dropped to the predetermined value due to the speeding up of the motor.

While the arrangement described in our 30 said application is entirely operative and practical for customary conditions imposed in accelerating and otherwise controlling an electric motor, the system leaves something to be desired for certain special applications, of 35 which I shall mention one by way of illustration. There are certain applications of motor control in which it is required that the motor accelerating switches shall in all events close successively to accelerate the motor in a plurality of definite accelerating steps, even 40 though the current taken by the motor is in excess of the predetermined value. Such a condition is met with in the control of steel mill auxiliary motors. In the operation of steel mills, and many other applications 45 where the load changes from time to time due to variations in temperature, misalignment, wear, tear, etc., the control of the electric driving motor in accordance with the current taken by the motor has certain disadvantages. For instance, if the load is ex-

ceedingly heavy on Monday morning due to the friction of the parts being high, it is necessary to adjust the control equipment to take care of the high value because it is required that the steel mill positively start. 55 After a few hours operation at this high value of adjustment, the adjustment may be changed for the ordinary conditions encountered. Ordinary steel mill operators and 60 electricians cannot be depended upon to make the proper readjustment of the current limit accelerating value, and experience has shown that these operators will adjust the equipment for a value of motor current at which the mill will be positively started and operated and then let the apparatus continue to 65 run with that adjustment. Time limit control overcomes the objections to current limit control which have been mentioned, but time limit control wastes a great deal of time under 70 some conditions. Thus, if the time limit is adjusted for the most severe conditions, it will be unnecessarily long for the ordinary 75 conditions. An accurate and reliable timing device is difficult to obtain, particularly a timing device which will always give the desired timing function. Time limit control also has the very serious objection that unless the timing is made as some function of an operating condition of the motor, a different 80 timing device is necessary for each different application of the motor control. 85 The present invention involves the use of the principle of controlling an electric motor in accordance with the rate of change of an electrical condition of the motor circuits, such, for example, as the rate of change of the motor current or the rate of change of the counter-electromotive force of the motor. Thus, when the motor is first connected to 90 the source of supply, there is a heavy rush of current and the rate of change of the current is comparatively high. If the motor accelerates, the rate of change of the motor current varies so that the rate of change approaches zero as the current taken by the motor becomes a substantially constant value. Also, when an accelerating resistor is short 95 circuited, the motor current again rises and falls and finally becomes a substantially con- 100

stant value. When the motor current becomes a substantially constant value, an accelerating step will be taken regardless of the value of the motor current. If the rate of change 5 of the generated or counter-electromotive force of the motor is the controlling function, the arrangement will be such that a control step will be taken when the counter-electromotive force of the motor is a substantially 10 constant value; that is, when the speed of the motor becomes a substantially constant value. Substantially definite time intervals will occur between the taking of the various control steps, so that the accelerating steps 15 will not follow each other too quickly, but in all events the control steps will be taken. In case the motor current reaches a dangerously high value, an overload protective device will be relied upon to protect the 20 motor.

In carrying my invention into effect in one form, I provide a system of control, as shown in Fig. 1, which has certain features of similarity to the system described and 25 claimed in the said joint application, Serial No. 354,030, filed January 26, 1920, and furthermore embodies the use of an electromagnetic switch or relay, as shown in Fig. 2, for which said Eugene R. Carichoff and myself 30 filed an application, Serial No. 421,291, November 2, 1920, a divisional application of the said application, Serial No. 354,030. The electromagnetic switch or electromagnetic relay described and claimed in the divisional 35 application, Serial No. 421,291, is connected so that one of the windings is energized to effect the opening of the switch, and the winding which is provided for governing the closing of the switch is energized in accordance 40 with the rate of change of an operating condition of the motor, such as the motor current, the speed of the motor, the counter-electromotive force or the voltage drop across an accelerating resistor, to hold the switch in 45 the open position until the selected condition has substantially ceased to change. In Fig. 3 I have shown a detail of a modification of the arrangement of Fig. 1 in which a series transformer having its primary connected in 50 the motor armature circuit and its secondary connected to the drop-out coils of the accelerating relays is used instead of the shunt transformer arrangement as in Fig. 1, and Fig. 4 is another detail of a modification in which 55 the shunt transformer is connected across the final accelerating resistor.

Referring to Fig. 1, the electric motor M having a series field F is energized from the source of supply through reversing contactors 11, 12, 13 and 14, the pair of contactors 11 and 14 being provided for connecting the motor to the source for operation in one direction and the pair of contactors 12 and 13 for connecting the motor to the source 65 for operation in the other direction. Resist-

ance in the armature circuit of the motor for limiting the current taken by the motor at starting is provided. In the embodiment of my invention, shown in Fig. 1, three sections R¹, R² and R³ of the starting resistance 70 are provided. The resistor R¹ is adapted to be short circuited by means of the electromagnetic switch or contactor 15, the resistor R² by the contactor 16, and the resistor R³ by means of the contactor 17. These resistor 75 switches are controlled by means of electromagnetic switches or relays which are controlled responsively to the rate of change of the counter-electromotive force of the motor. The resistance contactors are themselves 80 therefore controlled responsively to the rate of change of the counter-electromotive force of the motor, the arrangement being such that when the motor speeds up at starting 85 and the counter-electromotive force of the 90 motor has become substantially constant in value, the contactor 15 is energized to close and short circuit the section R¹, whereupon the motor current again rises, the motor accelerates and the counter-electro-motive 95 force increases. When the current again drops or the counter-electro-motive force again becomes a substantially constant value, the contactor 16 closes, followed by the contactor 17 when the motor speeds up and the 100 motor current again becomes constant. The normally closed relays 18 and 19 are provided for controlling the first resistance contactor 15, the normally closed relay 20 for controlling the contactor 16, and the normally 105 closed relay 21 for controlling the contactor 17. A master controller 22 is provided for controlling the starting, stopping and reversal of the motor, and a line switch 23 is provided for controlling the connection 110 of the motor and its control apparatus to the source of supply.

The relays 18 to 21 inclusive, which are shown very diagrammatically in Fig. 1, are shown in more detail in Fig. 2. Each of these relays is substantially identical in construction, although the windings of the relays 18 and 19 are connected in a different manner than are the windings of the relays 20 and 21. For purposes of explanation the relay 20 will be described. This relay comprises a stationary contact 24 and a movable contact 25 for controlling the energization of the coil winding of the contactor 16, the movable contact 25 being connected to the pivoted and movable member 26, to which the armature 27 of the upper coil 28 is connected and to which the armature 29 of the lower coil 30 is also connected. The member 26 carrying the contact 25 is biased 115 to the unattracted position, that in which the contacts 24 and 25 make engagement, by means of the spring 31. In the embodiment 120 of our invention shown in Fig. 1, the relays are shown as being normally closed but 125 130

my invention is not necessarily limited thereto, but is likewise applicable to an arrangement in which the relays are normally open. The armature 27 is supported by a bolt 32 having a screw thread whereby the armature may be very nicely adjusted with respect to the core 33 of the electromagnet of which the winding 28 forms a part. A friction member 34 having a certain amount of resiliency is provided for retaining the armature 27 in the position to which it has been moved. The lower armature 29 is likewise mounted on a bolt 35 having a screw thread and a resilient friction device 36 for holding the armature in the position to which it has been adjusted with respect to the core 37 of the electromagnet of which the winding 30 forms a part. It will be observed that the magnetic structure of the upper electromagnet is substantially independent of that of the lower electromagnet and that the two electromagnets may be adjusted substantially independently of each other. The winding 28 of the upper electromagnet is connected across the secondary of the potential transformer P. T. and the winding 30 of the lower electromagnet is connected across the first resistor R^1 . The electro-magnets are mounted on an insulating base or support 41.

The relays 18 and 19 are of similar construction to the relay 20, with the exception that the two independent electromagnets of the relay are connected in a particular manner to be presently explained. When the line switch 23 is closed, the two windings of the upper electromagnets of the relays are connected in series across the source of supply 10 and the windings of the lower electromagnets are also connected in series across the source of supply so that these relays are opened. When the master switch 22 is moved to the right so as to energize the contactors 12 and 13 for motor operation in one direction, the upper winding of relay 19 is connected across a part of the starting resistance and the upper winding of relay 18 is connected across the remainder of the resistance and the motor armature, so that the relay 19 will close after a predetermined small interval of time. The adjustment will be such that the relay will positively close in all cases except where it would be particularly dangerous for the relay to close. The electromagnetic resistance switch 15 is thereby energized to close to initiate the successive closing of the resistance switches as the motor increases in speed or the current taken by the motor becomes a constant value. It will be observed that when the contactor 13 closes the winding of the lower electromagnet of relay 19 is short circuited so as to give the control of the closing of the relay to the upper electromagnet after an interval of time. The winding of the lower electromagnet of relay 18 is connected across the source of supply. Likewise when

the master controller 22 is turned to the left, the line contactors 11 and 14 are energized to close and the upper winding of relay 18 is connected across the same part of the resistance as was previously the upper winding of the relay 19, the upper winding of relay 19 in this instance being connected across the remainder of the resistance and the motor armature. The lower winding of relay 18 is short circuited by contactor 14 and after an interval of time the closing of this relay is given to the upper winding. This time interval is desirable to take up the "slack" in gears and other parts driven by the motor. The relay 19 will close after an interval and effect the closing of the resistance switch 15, but the relay 18 will be held open due to the energization of both of its windings. When the motor has been operating in one direction and the master controller is thrown quickly through the off position to the other operative position, these relays 18 and 19 will prevent the resistance switches 15, 16 and 17 from closing until the current taken by the motor has been decreased to a predetermined value. The motor can therefore be "plugged", that is, reversed quickly by throwing the master switch quickly from the one operative position to the other, without serious injury to the motor, since when the master switch is thrown quickly from one operative position to the other, the starting resistance will all be reinserted in the motor armature circuit and this resistance will not be cut out until the motor armature current has dropped to a predetermined value.

As soon as the motor is connected to the source, there will be a voltage drop across the starting resistance and the relays 20 and 21 will automatically open, the pulls of the upper relay coils supplementing the pulls of the lower coils to effect the opening. The closing of resistance contactor 15 deenergizes the winding 30 of relay 20, and the closing of resistance switch 16 deenergizes the winding of the lower electromagnet of relay 21. These lower electromagnets are provided for effecting the opening of the relays and effecting a sequence, and the upper electromagnets are provided for governing the closing of the relays. Since the winding 28 of the upper electromagnet is energized from the secondary of the shunt or potential transformer P. T. when the resistance contactor 15 closes, the opening coil 30 will be deenergized and the relay will be held in the open position by means of the winding 28 until the counter-electromotive force of the motor has become substantially constant and the voltage induced in the secondary of the shunt transformer has become a predetermined minimum value. The relay will then close, thus energizing the resistance contactor 16 to close and short circuit the section R^2 of the starting resistance. The closing of the con-

tactor 16 in a similar manner deenergizes the lower or opening coil of the relay 21 and permits this relay to close when the rate of change of the counter-electromotive force of the motor has become substantially constant.

As thus constructed and arranged, and with the parts in the relative positions shown in Fig. 1, the operation of my invention is as follows:

- 10 In order to start the motor, the line switch 23 will first be closed, thereby connecting the upper winding of the relay 18 and the upper winding of the relay 19 in series across the supply circuit, and the lower windings of 15 these relays in series across the supply circuit. These relays will therefore open against their bias to the closed position. The master switch 22 will then be moved, say for instance, to the right to its first operative position, thereby energizing the pair of reversing contactors 12 and 13 to close so as to connect the motor to the source of supply with all of the starting resistance in the motor circuit. When the contactors 12 and 13 close, 20 the upper winding of relay 19 will be connected across the portion R_x of the resistor R^1 and the upper winding of the relay 18 will be connected across the remainder of the resistance and the motor armature. The lower 25 winding of relay 19 will be short circuited by contactor 13 and the lower winding of relay 18 will be connected across the source of supply. The closing of the motor circuit will effect the opening of the normally closed relays 30 35 20 and 21, since the lower or opening coil 30 of the relay 20 is energized responsively to the voltage drop across the resistor R^1 , and the upper or closing coil 28 is energized responsively to the rate of change of the 40 counter-electromotive force of the motor, which is responsive to the rate of change of the motor current. The lower or opening coil of the relay 20 is energized responsively to the drop across the resistors R^1 and R^2 , 45 and the upper or closing coil is energized responsively to the rate of change of the counter-electromotive force of the motor. The voltage drop across the section R_x will be insufficient to hold the relay 19 open so that 50 this relay will close its contacts after an interval of time in accordance with its bias. The setting of this relay will be such that the relay will positively close unless the motor current is a dangerously high value. The 55 resistance contactor 15 will not be closed, however, until the master controller is moved to its second operative position, thereby completing a circuit for the coil winding of the contactor 15 through the contacts of the relay 60 19 and the segments 38 of the master controller. The closing of the contactor 15 will deenergize the lower or opening coil 30 of the relay 20, but this relay will not close since it is held in the open position by means of the 65 upper or closing coil 28. The short circuit-

ing of the resistor R^1 will cause the motor current to rise quickly and then fall again as the motor speeds up. This will induce a current in the secondary of the potential transformer P. T. which will be responsive to the rate of change of the counter-electromotive force of the motor. As soon as the motor current has become substantially constant and the motor speed has become substantially constant, the winding 28 will not be energized sufficiently to hold the relay in its open position against its bias to the closed position, so that the relay will automatically close its contacts. The contactor 16 will not be energized to close, however, until the master controller is moved to the third operative position, thereby energizing the coil winding of the contactor 16 through the contacts 24 and 25 of the relay 20, the segment 39 of the master switch and the contacts of relay 19. The air gap between the armature of the holding electromagnet 28 and the core 33 thereof is such that after the relay closes, the change of current caused by the closing of the contactor 16 will not cause the relay to reopen.

The closing of contactor 16 will deenergize the lower or opening coil of the relay 21, and this relay will be held in the open position by means of the upper or closing coil, so that when the voltage induced in the secondary of the potential transformer P. T. has decreased to the predetermined value, the relay 21 will close its contacts in accordance with its bias. The contactor 17 will not be closed until the master switch has been moved to the fourth operative position so that the coil winding of the contactor 17 may be energized from the source of supply through the contacts of the relay 21, the segment 40 of the master switch and the contacts of relay 19. Because of the air gap between the armature and the core of the holding electromagnet of the relay 21, this relay will not automatically reopen when the contactor 17 closes and the rate of change of the current is thus varied.

If desired, the master switch 22 can be at once thrown directly to the fourth operative position and the resistance contactors will be automatically closed in succession responsively to the rate of change of the counter-electromotive force of the motor. The automatic closing of the resistance contactors can be arrested at any time by moving the controller backward to either the third, second or first operative position of the controller. For instance, if the master controller is first thrown to the fourth position and the automatic cutting out of the resistance has proceeded until the contactor 16 has closed; if the controller is moved backward to the second position, the successive closing of the contactors will be arrested, the contactor 16 will be opened, but the contactor 15 will be maintained closed.

In case the master controller 22 is first thrown to the left, the upper winding of relay 18 will be connected across the part R_x of the starting resistance R^1 and the upper winding of the relay 19 will be connected across the remainder of the resistance to the motor armature. The reversing contactors 11 and 14 will close and the lower electromagnet of relay 18 will be short circuited by the contactor 14 and the lower electromagnet of relay 19 will be connected across the supply circuit. After an interval of time, determined by the time taken by the short circuited lower electromagnet to release, the relay 18 will close to initiate the automatic cutting out of the starting resistance in the same manner as described in connection with the relay 19 when the controller was moved from its off position toward the right. It will be understood, of course, that when the master controller is moved to the left, the pair of reversing contactors 12 and 13 will be deenergized and the pair 11 and 14 will be energized to connect the motor to the source for operation in a different direction than that occasioned by the closing of the contactors 12 and 13. If the master controller has been thrown to the fourth or full running position to the right and the motor is operating in that direction and it is desired that the motor be quickly reversed, this may be done by throwing the master controller quickly to the fourth or full running position to the left. The pair of contactors 12 and 13 will thereupon be opened, the resistance contactors will all be automatically opened, the relay 19 will be opened, relay 18 is already open, and the pair of reversing contactors 11 and 14 will be closed. The motor will then be connected to the source for operation in the reverse direction with all of the starting resistance included in the motor circuit. This is called "plugging" the motor, and it will cause no damaging effects on the motor since all of the starting resistance has been included in the motor armature circuit so as to cut down the rush of current. When the motor is "plugged" in that manner a heavy rush of current occurs because of the fact that the generated potential of the motor is assisting the line potential. The relay 18 will be held open temporarily by the upper electromagnet due to the voltage drop across R_r . When the generator action of the motor has substantially ceased and current in the motor armature circuit has decreased to a predetermined value, the relay 18 will close its contacts to initiate the successive operation of the resistance contactors in the manner previously described. The relay will be set to close when the motor has substantially come to rest.

It will be observed that the magnetic circuits of the relay coils are independent of each other and that the relays 18 to 21 inclu-

sive are all capable of a wide range of adjustment. The values at which the relays will open and close may be varied independently of each other, and this wide range of permissible adjustment makes the system suitable for all kinds of service in which it is desirable that the accelerating steps be positively taken. It will also be noted that the same relays and coils may be used for all sizes of motors of substantially the same voltage, thereby effecting a simplification and reduction of the cost of control equipments and necessitating the carrying of very few spare parts in stock. Since there are no interlocking contacts, a great many operating troubles are eliminated, the wiring is very simple, and less time and labor will be required in building a control equipment. The relays have no mechanical connection with the resistance contactors and may be located in any desirable place, or may be locked up away from unauthorized persons and away from dirt. The contact parts of the relay are vertical and will thus retain a minimum amount of dirt. The relays, when of the normally closed type, are never called on to break a circuit and thus may be made quite simple and inexpensive, since the closing of a circuit is relatively simple as compared to breaking a circuit, especially an inductive circuit. Because of that fact, the movement of the relay contacts may be anything desired, and the pick-up and drop-out values of the relay may be adjusted without regard to the distance which separates the contacts when the relay is open. Because of the wide range of permissible adjustment, either one of the relay coils may be connected so as to assist in effecting the opening of the relay or be connected as the coil which governs the closing of the relay. Since one of the relay coils is deenergized when the preceding resistance contactor closes, there is little tendency to open the relay or to diminish the pressure on the relay contacts due to the change in current when the resistance is cut out.

A further important advantage obtained by the use of the particular form of relay is that a time limit characteristic in cutting out the starting resistance may be had. Thus, when the coil 30 of relay 20 is short circuited by the closing of the resistor switch 15, the coil is not instantly deenergized because of its inductive effect, and the armature 29 will therefore be maintained in the attracted position for an appreciable interval of time. This time interval may be varied by varying the position of the armature 29 on the threaded bolt 35, since the nearer the armature to the core of the electro-magnet, the longer the armature will be held by the magnetization after the coil has been deenergized. A time interval may also be had due to the short circuiting of the lower coils of the relays 18 and 19.

When a shunt transformer is used as in Fig. 1, the accelerating contactors are closed in accordance with a function of the rate of change of the motor current and with a time function. 5 If the transformer has inductance (L) and resistance (R) factors so proportioned that the ratio L/R is large, then the transformer will function more as a timing device than as a rate of change device. If the ratio L/R is 10 small, then the transformer will have to be larger, but it will function more as a rate of change device. The impressed voltage on the primary of the transformer P. T. will increase as a function of the speed of the motor 15 and the current induced in the secondary of the transformer will be in one direction, approaching zero only when the motor speed has ceased to increase. This produces a result which is desirable for a motor control 20 arrangement, and the L/R factor may be used as best suited to the work to be performed without being otherwise restricted.

In the arrangement shown in Fig. 3, the transformer C. T. is of the series type and is 25 connected in series with the motor armature. The secondary of this transformer is connected to energize the holding coils of the relays 20 and 21 in the same manner as the secondary of the shunt transformer P. T. of 30 Fig. 1. It is considered that those skilled in the art will understand the complete control from the suggestion given in Fig. 3, since the sole difference consists in connecting the primary of the transformer in series with 35 the motor armature instead of in shunt therewith. In this arrangement the control of the resistors is a combined rate of change of the motor current function and a time function with the rate of change function as 40 the predominating factor. Both rate of change and time functions are desirable for a practical control arrangement. The shunt transformer arrangement of Fig. 1 has the 45 advantage over the current transformer arrangement as in Fig. 3 in that the transformer is more readily susceptible of a practical design to obtain the desired relation between the rate of change and the time functions.

50 In the arrangement of Fig. 4, which like Fig. 3 is merely a detail showing how the arrangement of Fig. 1 may be modified, the primary of the shunt transformer P. T. is connected across the final starting resistor 55 R₃. The transformer is therefore energized responsively to the rate of change of the voltage drop across this resistor. This arrangement has certain of the advantages of the arrangement of Fig. 1, and in addition 60 the advantage that the transformer is de-energized when the resistor contactor 17 closes. It furthermore has the advantage 65 that the primary of the transformer may be connected across more or less of the starting resistors or be connected across only a por-

tion of the resistor R₃. This permits of readily adjusting the arrangement to obtain the desired control of the relays 20 and 21.

In the arrangements of Figs. 1, 3 and 4, the current taken by the motor in starting 70 first increases very rapidly and then decreases more slowly. In the arrangements of Figs. 3 and 4, if the excitation of the respective transformers exactly follows this change, the induced current in the secondary 75 will be in one direction during the increasing period and in the opposite direction during the decreasing period. But since there is a lag due to the relationship of L/R, the induced current may go through 80 zero at a critical period and let the next successive resistor contactor close before it should. For this reason, if the transformer is connected as shown in either Fig. 3 or Fig. 4, the transformer should function more 85 as a timing device than as a rate of change device to give the desired positive action of the relays 20 and 21.

In accordance with the provisions of the patent statutes, I have described the principle of operation of my invention, together 90 with the apparatus which I now consider to represent the best embodiment thereof; but I desire to have it understood that the apparatus shown is only illustrative, and that 95 the invention can be carried out by other means.

What I claim as new and desire to secure by Letters Patent of the United States, is,—

1. A control system for electric motors comprising a resistor, an electromagnetic switch having a switch member normally in one position for controlling the resistor, the 100 said switch having two windings which successively control the operation of the switch member, one of which is energized to govern the operation of the switch member to a second position and the other of which is energized responsively to the rate of change 105 of a motor operating condition to govern the operation of the switch member to the normal position.

2. A control system for electric motors comprising a resistor, an electromagnetic switch having a switch member normally in one position for controlling the resistor, the 115 said switch having two windings which successively control the operation of the switch member, one of which is energized to govern the operation of the switch member to a second position and the other of which is energized while a condition of the motor circuit is changing to hold the switch member in the second position and to then release the 120 switch member to return to the normal position when the said condition of the motor circuit has substantially ceased changing.

3. A control system for electric motors comprising a resistor, a normally closed electromagnetic switch for controlling the re- 125

- 5 sistor, the said switch having two windings, one of which is energized in accordance with the voltage drop across the resistor and governs the opening of the switch and the other of which is energized in accordance with the rate of change of a motor operating condition and governs the closing of the switch. 70
- 15 4. A control system for electric motors comprising a starting resistor, a normally closed electromagnetic switch for controlling the resistor, the said switch having two windings, one of which is energized to effect the opening of the switch and subsequently automatically deenergized, and the other of which is energized in accordance with the rate of change of a motor operating condition to hold the switch open until the said motor operating condition has become substantially constant. 75
- 20 5. A control system for electric motors comprising a plurality of resistors, normally closed successively operated electromagnetic switches for controlling the resistors, each of the switches having a winding for opening the switch effective to hold the switch open until the preceding switch closes, and means energized responsively to the rate of change of a motor operating condition for holding the switches open until the said motor operating condition has become substantially constant. 80
- 25 6. A control system for electric motors comprising a plurality of resistors, normally closed successively operated electromagnetic switches for controlling the resistors, each of the switches having a winding for opening the switch which is deenergized by the closing of a preceding switch and a winding for controlling the closing of the switch which is energized in accordance with the rate of change of a motor operating condition. 85
- 30 7. A control system for electric motors comprising a plurality of resistors, normally closed successively operated electromagnetic switches for controlling the resistors, each of said switches having a winding energized responsively to the voltage drop across a preceding resistor for opening the switch, and a winding energized responsively to the rate of change of a motor operating condition for holding the switch open until the said motor operating condition has become substantially constant. 90
- 35 8. A control system for electric motors comprising a plurality of resistors, a plurality of normally open electromagnetic switches for short circuiting the resistors, normally closed electromagnetic relays for controlling the operation of the said electromagnetic switches, each of said relays having two cooperating windings, one of the windings being connected across one of the resistors to open the relay, and the other winding energized responsively to the rate 95
- 40 of change of the motor current to hold the relay open until the motor current has become substantially constant. 100
- 45 9. A control system for electric motors comprising an electromagnetic switch having a switch member biased to one position for controlling the motor, the said switch having two windings, one of which governs the operation of the switch member to another position, a transformer connected to be energized in accordance with conditions in the motor circuit, and connections whereby the other switch winding is energized from the secondary of the said transformer to govern the return of the switch member to its biased position. 105
- 50 10. A control system for electric motors comprising a source of supply, motor circuit energized from said source, a switch for controlling the said circuit, the said switch having a switch member and two windings which control the operation of the switch member, one of said windings being connected to the motor circuit to be energized in accordance with a difference in voltage between points in the motor circuit which varies due to a changing operating condition of the motor and which is of a value less than the voltage of the said source, and the other of said windings being inductively related to the motor circuit to regulate the operation of the switch in accordance with the rate of change of a changing condition of the motor circuit. 110
- 55 11. A control system for electric motors comprising a motor circuit, a switch for controlling the acceleration of the motor, the said switch having a switch member and two windings which control the operation of the switch member, one of said windings being connected to be energized responsively to the difference in voltage between points in the motor circuit for holding the switch member in the open position, and the other of said windings being inductively related to the motor circuit to govern the operation of the switch member to the closed position in response to the rate of change of the potential difference between points in the motor circuit. 115
- 60 12. A control system for electric motors comprising a motor circuit, a resistance in said circuit, an electromagnetic switch for controlling a portion of said resistance, the said switch having two windings which control the operation of the switch, one of said windings being connected to be energized responsively to the drop in potential across a portion of said resistance for magnetically holding the switch in the open position and the other of said windings being inductively related to the motor circuit to regulate the closing of the switch. 120
- 65 13. A motor control system comprising a motor circuit including a motor armature, 125

switch contact mechanism for controlling the said circuit to control the motor, an electro-responsive device having a primary winding connected across the motor armature and a 5 secondary winding inductively related to said primary winding, and means governed by the said secondary winding for governing the operation of said switch contact mechanism in accordance with the rate of change 10 of the generated potential of the motor armature.

14. A control system for electric motors comprising electro-responsive motor controlling means, a transformer having its primary 15 connected across the motor armature, and connections whereby the said means is energized from the secondary of the transformer to control the motor.

15. A control system for electric motors 20 comprising a motor, a resistor, electro-responsive switch mechanism for controlling the resistor, and an electro-responsive device having one winding connected in multiple relation with the motor armature and a second 25 winding inductively related thereto for controlling the said switch mechanism whereby the said switch mechanism is energized to close and short circuit the resistor when the counter electromotive force of the motor 30 has substantially ceased to change.

16. A control system for electric motors comprising a motor, a resistor, electro-responsive switch mechanism for controlling the resistor, and a transformer having its 35 primary connected across the motor armature and its secondary connected to control the said switch mechanism whereby the said switch mechanism is energized to close and short circuit the resistor when the voltage 40 drop across the motor armature has substantially ceased to change.

17. A control system for electric motors comprising an electromagnetic switch having a switch member normally in one position for 45 controlling the motor, the said switch having two windings which successively control the operation of the switch member, one of which is energized to govern the operation of the switch member to a second position, and 50 means responsive to the rate of change of an operating condition of the motor for controlling the energization of the other of said windings to govern the operation of the switch member to the normal position.

18. A control system for electric motors 55 comprising a resistor for controlling the motor, an electromagnetic switch having a switch member normally in one position for controlling the resistor, the said switch having two windings which successively control the operation of the switch member, one of which is energized to govern the operation of the switch member to a second position, and 60 means for supplying a current which is proportional to the rate of change of an elec-

trical condition of the motor circuit to the said other winding to govern the operation of the switch member to the normal position.

19. A control system for electric motors comprising an electro-responsive switch having a switch member biased to one position for controlling the motor, means for operating the said switch member to a second position, and electro-responsive means for exerting on the said switch member a holding force which varies responsively to the rate of change of the difference of potential between points in the motor circuit to hold the switch member in the second position until the potential difference between the said points becomes a substantially constant value. 70

20. A control system for electric motors comprising a resistor in the motor circuit, an electro-magnetic switch for controlling the said resistor, an electromagnetic relay having a switch member biased to one position for controlling the energization of the said electromagnetic switch, the said relay having two windings which successively control the said switch member, and connections whereby the first winding of the said relay is energized to operate the relay to a second position and is subsequently deenergized, and the second winding of the relay is energized in accordance with the rate of change of the motor current to hold the said switch member in the second position until the motor current has become substantially constant. 80

21. A control system for electric motors comprising an electro-responsive switch having a switch member biased to one position for controlling the motor, electro-responsive means for operating the said switch member to a second position, a second electro-responsive means for holding the switch member in the second position, an electro-responsive device connected to be energized in accordance with the rate of change of the difference of potential between points in the motor circuit, and connections whereby the energization of the said second electro-responsive means is controlled by the said device so as to hold the said switch member in the second position until the change in the difference of potential between said points in the motor circuit substantially ceases. 90

22. A control system for electric motors comprising an electromagnetic switch having a switch member biased to one position for controlling the motor, an electromagnet for operating the switch member to a second position, a second electromagnet for holding the switch member in the second position, an electro-responsive device connected to be energized in accordance with the rate of change of the motor armature voltage, and connections whereby the energization of the said second electromagnet is controlled by the said device so as to hold the said switch mem- 100

- ber in the second position until the change in the motor armature voltage substantially ceases.
23. A control system for electric motors comprising an electromagnetic switch having a switch member biased to one position for controlling the motor, an electromagnet for operating the said switch member to the second position, a second electromagnet for holding the switch member in the second position, a transformer having its primary connected across points in the armature circuit of the motor, and connections whereby the said second electromagnet is energized from the secondary of the said transformer to hold the said switch member in the second position until the motor current has become substantially constant.
24. A control system for electric motors comprising an electromagnetic switch having a switch member biased to one position for controlling the motor, an electromagnet for operating the said switch member to the second position, a second electromagnet for holding the switch member in the second position, a transformer having its primary connected across the motor armature, and connections whereby the said second electromagnet is energized from the secondary of the said transformer to hold the said switch member in the second position until the counter-electromotive force of the motor has become substantially constant.
25. A control system for electric motors comprising a motor circuit, a resistor in said circuit, an electromagnetic switch for controlling the resistor, the said switch having two windings, one of which is connected to be energized responsively to the current taken by the motor to hold the switch in the open position, and the other of which is connected to the motor circuit to set up a magnetic force which varies responsively to the rate of change of a motor operating condition to govern the closing of the switch.
26. A control system for electric motors comprising resistance in the motor circuit, electromagnetic switch mechanism for controlling the resistance, means operated responsively to the value of the motor current for holding the said switch mechanism in the open position and means responsive to the rate of change of a motor operating condition for controlling the closing of said switch mechanism.
27. A control system for electric motors, comprising resistance in the motor circuit, electromagnetic switch mechanism for controlling the resistance, means responsive to the value of the motor current for initiating the operation of the said switch mechanism, and means responsive to the rate of change of a motor operating condition for controlling the subsequent operation of the said switch mechanism.
28. A control system for electric motors, comprising two resistors in the motor circuit, electromagnetic switches for controlling the said resistors, means responsive to the value of the motor current for controlling one of the said switches, and means responsive to the rate of change of an operating condition of the motor for controlling the other of the said switches.
29. A reversing control system for electric motors, comprising two resistors in the motor circuit, electromagnetic switches for controlling the said resistors, electro-responsive reversing switch mechanism, a reversing controller for controlling the said switches and the said switch mechanism, means responsive to the value of the motor current for controlling one of the said resistor switches, and means responsive to the rate of change of an operating condition of the motor for controlling the other resistor switch.
30. A reversing control system for electric motors, comprising two resistors in the motor circuit, electromagnetic switches for controlling the said resistors, electro-responsive reversing switch mechanism, a reversing controller for controlling the said switches and the said switch mechanism, a relay energized responsively to the voltage drop across one of the resistors for controlling the corresponding resistor switch, and a relay energized responsively to the rate of change of a motor operating condition for controlling the other of said resistor switches.
31. A control system for electric motors, comprising resistance in the motor circuit, and means operated responsively to the voltage drop across the resistance for controlling the resistance to stop the motor and responsively to the rate of change of a motor operating condition for controlling the resistance to accelerate the motor.
32. A control system for electric motors, comprising resistance in the motor circuit, means operated responsively to the voltage drop across the resistance for controlling the resistance to stop the motor, and means operated responsively to the rate of change of a motor operating condition for controlling the resistance to accelerate the motor.
33. A control system for electric motors, comprising a plurality of resistors in the motor circuit, electro-responsive means operated responsively to the voltage drop across one of the resistors for controlling the stopping of the motor, and electro-responsive means operated responsively to the rate of change of a motor operating condition for controlling the remainder of the resistors to accelerate the motor.
34. A control system for electric motors, comprising a plurality of resistors in the motor circuit, electromagnetic contactors for controlling the said resistors, electro-respon-

sive reversing switch mechanism for controlling the direction of motor operation, a pair of relays under the control of the said reversing switch mechanism for controlling one of the said resistor contactors, a relay energized responsively to the rate of change of a motor operating condition for controlling each of the remainder of the said contactors, a reversing controller, and connections whereby when the motor is reversed one or the other of the said pair of relays is closed responsively to the voltage drop across the first mentioned resistor to energize one of the contactors to short circuit the said first mentioned resistor.

35. A control system for electric motors comprising a resistor in the motor circuit, normally closed switch mechanism for controlling the resistor, means responsive to the value of the motor armature current for operating the said switch mechanism to the open position and holding the same therein, and means responsive to the rate of change of a motor operating condition for influencing the closing of said switch mechanism.

36. A control system for electric motors comprising a resistor in the motor circuit, an electroresponsive switch having a switch member biased to one position for controlling the resistor, means for operating the said switch member to a second position, and electroresponsive means separate from said first means inductively related to the motor circuit for causing to be exerted on said switch member a magnetic holding force which varies responsively to the rate of change of a changing condition of the motor to influence the return of the switch member to the first position.

37. A control system for electric motors comprising a resistor, a normally closed electromagnetic switch for controlling the resistor, the said switch having two windings, one of which is connected to be energized in accordance with the value of the motor armature current and governs the opening of the switch and the other of which is connected to be energized in accordance with the rate of change of a motor operating condition and influences the closing of the switch.

38. A control system for direct current motors, comprising a resistor in the motor circuit, an electromagnetic switch for controlling the resistor, a relay for controlling said switch, the said relay having a winding connected to be energized responsively to the motor current for effecting the initial operation of the relay and a winding energized responsively to the rate of change of a motor operating condition for influencing the subsequent operation of the relay.

39. A control system for electric motors comprising a motor circuit, a switch for controlling the acceleration of the motor, the

said switch having a switch member normally in the closed position and two windings which influence the operation of the switch member, one of said windings being connected to the motor circuit to be energized responsively to the value of the motor current for effecting operation of the switch member to the open position and the other of said windings being inductively related to the motor circuit for influencing the closing of the switch member.

40. A control system for direct current motors comprising a motor circuit, means comprising an electroresponsive device for controlling the motor speed, the said device having two cooperating windings, one of which is connected to respond to variations in the value of the current in the motor circuit and the other of said windings being inductively related to the motor circuit, the said device having a movable element which is operated to one position under the influence of both of said windings and returned to the initial position thereof under predetermined conditions under the control of one of said windings alone.

41. A control system for direct current motors, comprising a resistor arranged to be included in the motor circuit and having a plurality of sections, a contactor for shunting each of said sections, a separate relay for controlling each of said contactors, the said relays being interconnected for operation in a definite sequence to effect a definite sequence of operation of said contactors, each of said relays having a switch member and two windings which cooperate to control the same, one of said windings being connected to be energized to effect the initial operation of the switch member and the other of said windings being connected to respond to the rate of change of a motor operating condition to influence the subsequent operation of the switch member.

42. A control system for electric motors comprising a resistor, switch mechanism for controlling said resistor, electroresponsive means for operating said switch mechanism from a first position to a second position, and electroresponsive means separate from said first means for regulating the supply of current to operate the said switch mechanism to the first position in accordance with the rate of change of the potential difference between points of the motor circuit and a time function.

43. A control system for electric motors comprising a resistor, switch mechanism for controlling the resistor, means responsive to the value of the motor current for opening said switch mechanism, and electroresponsive means separate from said first means responsive to the potential difference between points in the motor circuit for controlling

the closing of said switch mechanism to short circuit the resistor an interval of time after said potential difference has substantially ceased to change.

In witness whereof, I have hereunto set my hand this 5th day of January, 1922.

BENJAMIN W. JONES.
